[57] ABSTRACT

An internal combustion engine, particularly for the drive of motor vehicles, in which the lubricating oil is returned by way of a return line from one end of the cylinder head into the end of the oil sump disposed opposite to the end of the cylinder head which is provided with a collecting pot so that the lubricating oil is conducted from the cylinder head directly into the collecting pot of the oil sump.

PATENTED JAN 15 1974

3,785,457

INTERNAL COMBUSTION ENGINE

The present invention relates to an internal combustion engine, especially to an internal combustion engine for the drive of vehicles, in which the lubricating oil is returned from the end of the cylinder head disposed opposite the end of the oil sump, into the oil sump which is provided with a collecting pot.

Internal combustion engines with oil returns of this type exhibit a relatively high drag power because the oil flowing off from the cylinder head at first flows through the oil pan before it reaches the collecting pot of the oil pan. The oil level in the oil sump is not insignificantly increased by the oil flowing off from the cylinder head whose quantity may amount up to 30 percent of the total oil quantity so that the drive unit of the internal combustion engine has to produce a large oil-splash-work.

The present invention is concerned with the task to avoid the described disadvantage. The underlying problem is thereby solved according to the present invention in that a return line is provided which conducts the lubricating oil from the cylinder head directly into the collecting pot of the oil sump.

The quantity of lubricating oil flowing through the oil sump is reduced in a very simple manner by the present invention. The oil level in the oil pan remains low. The drag power of the internal combustion engine remains small.

Accordingly, it is an object of the present invention to provide an internal combustion engine which avoids by simple means the aforementioned shortcomings and drawbacks.

Another object of the present invention resides in an internal combustion engine, especially for driving motor vehicles, in which the drag power is decreased by reducing the oil-splash-work to be performed by the engine.

A further object of the present invention resides in an internal combustion engine in which the amount of lubricating oil flowing through the oil sump is reduced.

Another object of the present invention resides in an internal combustion engine in which the oil level in the oil sump remains relatively low notwithstanding the return of substantial oil quantities from the cylinder head.

These and other objects, features and advantages of the present invention will become more apparent from the following description when taken in connection with the accompanying drawing which shows, for purposes of illustration only, one embodiment in accordance with the present invention, and wherein

The single FIGURE is a schematic elevational view of an internal combustion engine in accordance with the present invention.

Referring now to the single FIGURE of the drawing, an oil pan or sump 3 is arranged underneath the cylinder block 2 of an internal combustion engine 1, illustrated only schematically; the oil pan 3 is provided at one end with a collecting pot 4. The cylinder head 5 with the cylinder head hood 6 is disposed above the cylinder block 2. In order to reduce the drag power of the internal combustion engine 1, a return line 7 is provided for the return flow of the oil from the cylinder head 5 which can take place by pumping action or by its own gravity with an inclined installation (dash line showing at inclination angle L) of the internal combus-

tion engine or with the arrangement of an inclined collecting channel in the cylinder head, whereby the inlet cross section of the return line 7 is disposed at the end of the cylinder head 5 which is disposed opposite the end of the oil sump 3 provided with the collecting pot 4. Although the drawing shows the oil return line 7 connected at the bottom of the hood 6, such connection can also be at the head 5 itself in engine arrangements where the oil collecting channel is formed below the hood. The return line 7 conducts the returning oil directly into the collecting pot 4 of the oil sump 3 so that the oil level in the oil sump 3 always remains low.

The arrangement of the return line becomes particularly advantageous when the internal combustion engine 15 is arranged in a motor vehicle 8 inclined downward toward the rear (dash line showing) as well as during mountain drives and accelerations.

While I have shown and described only one embodiment in accordance with the present invention, it is understood that the same is not limited thereto but is susceptible of numerous changes and modifications as known to those skilled in the art and I, therefore, do not wish to be limited to the details shown and described herein but intend to cover all such changes and modifications as are encompassed by the scope of the appended claims.

What I claim is:

1. An oil return arrangement for an internal combustion engine comprising:
a cylinder head of an internal combustion engine, a longitudinally extending oil sump arranged underneath said engine, said oil sump including an oil collecting pot having a substantially greater depth in the downward direction than other portions of said oil sump, and an oil return line leading directly from said cylinder head to said collecting pot in bypassing relationship to said other portions of said oil sump so as to minimize the oil level in said other portions of said oil sump with a consequent reduction in oil drag forces on moving engine parts disposed directly adjacent the oil sump.
2. An arrangement according to claim 1, wherein said collecting pot is positioned adjacent a first longitudinal end of said engine, and wherein said oil return line is connected at said cylinder head adjacent a second longitudinal end of said engine opposite said first end.
3. An arrangement according to claim 2, wherein said engine is mounted in a vehicle with said first end facing in the forward direction and the second end facing in a rearward direction.
4. An arrangement according to claim 3, wherein said engine is inclined downwardly in a rearward direction when said vehicle is in a level position.
5. An arrangement according to claim 1, wherein all portions of said oil return line extend in a downward direction from said cylinder head to said collecting pot.
6. An arrangement according to claim 2, wherein all portions of said oil return line extend in a downward direction from said cylinder head to said collecting pot.
7. An arrangement according to claim 4, wherein all portions of said oil return line extend in a downward direction from said cylinder head to said collecting pot.
8. An internal combustion engine comprising:
a cylinder head extending over an upper part of said engine,

a longitudinally extending oil sump arranged underneath said engine, said oil sump including an oil collecting pot having a substantially greater depth in the downward direction than other portions of said oil sump,

and an oil return line leading directly from said cylinder head to said collecting pot in bypassing relationship to said other portions of said oil sump so as to minimize the oil level in said other portions of said oil sump with a consequent reduction in oil drag forces on moving engine parts disposed directly adjacent the oil sump.

9. An engine according to claim 8, wherein said collecting pot is positioned adjacent a first longitudinal end of said engine, and wherein said oil return line is connected at said cylinder head adjacent a second longitudinal end of said engine opposite said first end.

10. An engine according to claim 9, wherein said engine is mounted in a vehicle with said first end facing in the forward direction and the second end facing in a rearward direction.

5 11. An engine according to claim 10, wherein said engine is inclined downwardly in a rearward direction when said vehicle is in a level position.

12. An engine according to claim 8, wherein all portions of said oil return line extend in a downward direction from said cylinder head to said collecting pot.

13. An engine according to claim 9, wherein all portions of said oil return line extend in a downward direction from said cylinder head to said collecting pot.

14. An engine according to claim 11, wherein all portions of said oil return line extend in a downward direction from said cylinder head to said collecting pot.
